ASPHALT OR RESIN SHIPPING CONTAINER

Oryville K. Schmied, Upper Montclair, N. J., assignor to Reynolds Research Corporation, Richmond, Va., a corporation of Delaware

Application June 8, 1940, Serial No. 339,416

2 Claims. (Cl. 206—84)

This invention generally relates to a new and novel shipping container, particularly adapted for the packaging and shipping of asphalt, and also for the packaging and shipping of natural and synthetic resins, rubber compounds and rubber derivatives, waxes, and various combinations thereof, and like substances which have certain characteristics similar to asphalt, namely, of being fluid and adhesive when heated, and relatively solid when at room temperatures.

Heretofore, asphalts and like materials have commonly been shipped in kegs, barrels, and tin and wood containers and various attempts have been made to line such shipping containers in such fashion so that the asphalt or like mass would not solidly adhere to the interior walls of the container when at room temperatures. When hot asphalt was poured molten into a keg for shipping, it became solidified, and the asphalt tenaciously adhered to the walls of the keg, and so it was necessary in order to remove the asphalt to literally chop pieces of the same out of the container; when this was done, either the relatively expensive container was ruined or substantial amounts of asphalt remained upon the side walls of the keg. Various linings suggested for the walls of such containers have not been widely acceptable commercially.

It has been suggested to treat the interior surfaces of metal containers for the shipping of asphalt with thin films of oxide of iron and also to treat such metallic walls with oxalic acid. It also has been suggested to treat the interiors of rubber cement paper packages with thick coatings of liquefied soap. It has also been suggested to line the interiors of fabric bags for shipping asphalt with coatings of clay. It has also been suggested to line the interiors of kraft paper packages for the shipping of asphalt with a higher melting point pitch or asphalt than the asphalt to be packed therein.

All of the prior art efforts to form a cheap, economical and convenient package for the shipping of asphalt or equivalent substances have been relatively unsuccessful.

Therefore, it is an object of my invention to provide a strippable film or lacquer coating upon a layer of aluminum foil as an interior surface upon a kraft paper liner for an asphalt shipping container formed of cheap and economical cardboard or the like.

It is also within the purview of my invention to mount the film coated or lacquer coated aluminum foil directly to the interior of a suitable cardboard or equivalent container.

It is a further object of my invention to provide a lacquer or similar film, particularly a cellulose acetate film upon an aluminum foil lining so that the said coating, since relatively non-adherent to the smooth aluminum foil, may be easily stripped therefrom; by this means, when molten asphalt is poured within the container and solidifies, the asphalt tenaciously adheres to the strippable acetate or other lacquer coating, but the latter is easily strippable from the foil thereby permitting the exterior paper or cardboard container to be stripped from the block of asphalt which adheres to, and is covered by the film or lacquer coating.

15 It is also within the purview of my invention to provide a cellulose acetate film as a coating upon foil lined shipping containers for asphalt or the like, which film when the temperature of the asphalt is raised to 400° F. or higher, for suitable periods, will disintegrate, and so be disposed of.

20 It is also a further object of my invention to provide an oil film or other non-adherent medium to prevent adhesion of asphalt, or other like substances, to an aluminum foil lining upon cheap and economical paper or cardboard shipping containers and in this conjunction, it will be observed that the metal lining protects the cardboard from highly heated substances packed within the containers, tending to prevent charring, and that such metal linings, being substantially impervious to liquids, also prevent leakage of the molten liquids and prevent the materials packed or the film coatings from impregnating or seeping through the fibrous package wall.

25 Other objects and advantages of the invention will appear from the description of preferred embodiments of the invention which are set forth for illustrative purposes only and in which changes may be made without departing from the spirit of the invention.

30 In the figures:
Fig. 1 is a perspective view of a cardboard shipping container with a liner, suitable for shipping asphalt, or the like, and embodying my invention;

35 Fig. 2 is an enlarged fragmentary cross section taken on the line 2—2 of Fig. 1;

40 Fig. 3 is a fragmentary section, partly broken away for purposes of clarity, of the liner illustrated in Fig. 2;

45 Fig. 4 is a fragmentary perspective, partly broken away, of the stock utilized in fabricating a modified embodiment of my invention wherein

the coated metal lining is directly mounted to a cardboard stock;

Fig. 5 is a fragmentary perspective, partly broken away, of a further modified embodiment of my invention wherein an oily film is applied to a metal foil lining directly mounted by means of adhesive to cardboard container stock.

Referring to Figs. 1, 2 and 3, a box like container 10 formed of heavy cardboard or corrugated paper or the like is provided with a liner 12. Liner 12 may be formed of 40 pound kraft paper 14 as a base, laminated to .0004" thick aluminum foil 16, using casein latex, or other suitable foil adhesives, as a laminating means, which latter is indicated as 18. The exposed foil surface is in turn, coated with a thin cellulose acetate film 20 which will normally be about .0003" thick. Such acetate film is relatively non-adherent to the metal and can be easily stripped therefrom.

It will be realized that various other equivalent relatively non-adhering plastic or lacquer films may be applied to the metal foil in place of the cellulose acetate film coating. Such films normally may be suitable cellulose derivatives, or suitable synthetic resins or mixtures thereof, but should be relatively non-adherent to metal. It is within the purview of my invention to pre-treat the metal foil surface with a medium, such as an oil film, before applying the strippable film thereto, in order to insure easy stripping and relative non-adherence to the metal layer; by such pretreatment of the metal, many ordinarily metal adherent films may be utilized as the strippable film. Preferably the metal surfaces and the lacquer or strippable film surfaces of the liner will be continuous and uninterrupted. The metal tends to prevent any charring effects in the paper due to highly heated asphalt or plastic substances packed within the container 10.

When molten asphalt is poured within the lined container 10, it tends to solidify into a solid block indicated at Fig. 2 as 22. The container may be shipped, and then when used, torn or stripped from the block of asphalt 22, leaving the asphalt covered by the film coating 20 which is relatively non-adherent to the metal foil 16 but which is adherent to the asphalt block 22.

If the asphalt block with the adherent film of cellulose acetate 20 is heated approximately to 400° F. for a suitable period, it will be observed that the acetate film disintegrates and is dissipated into the molten asphalt for all practical purposes, and my invention includes other equivalent dissipating films.

It will be recognized that such a lined shipping container 10 may be utilized for the shipping of various plastics, natural and synthetic, resins, rubber derivatives, waxes, and compounds thereof, and the like which have certain properties generally similar to asphalt, namely, the characteristics of being relatively solid at room temperature and which when poured in heated molten condition into a shipping container are tenaciously adherent when solidified to the shipping container walls, and therefore, the utilization of the shipping containers herein described for such substances is included within the purview of my invention.

It will be further recognized that the metal foil while preferably aluminum and of the gauge described, may be formed of copper, zinc or the like. The gauges of the metal foil may of course, vary from .0003" to .002" thick.

The metal foil has the advantage of presenting 75

a relatively smooth non-adherent surface to which the acetate layer does not readily bond and from which it may be readily stripped. Also, the metal layer serves to seal and protect the paper or cardboard from the foil coating and from the contents of the containers. It will be recognized that heretofore a relatively impervious surface such as afforded by the metal foil, was only approached by expensive all metal containers which made costs practically prohibitive.

It will be further recognized that various other forms of containers might be lined with a film coated or a lacquer coated metal foil and so such containers formed of light woods or the like are considered within the purview of my invention. The liner base instead of being 40 pound kraft paper, could be formed of much lighter stock, such as 10 pound tissue, or in fact, could be as heavy as cardboard.

Fig. 4 is a fragmentary perspective of a container 24 formed generally similar to container 10 but having no liner; in this instance container 24 may have the foil 16 directly mounted upon its interior surfaces by the adhesive 18 and be in turn overcoated with the film coating of cellulose acetate 20, or the like, it being understood that the elements 16, 18 and 20 will be similar as described above.

As indicated in Fig. 5 by a fragmentary perspective similar to the perspective shown in Fig. 4, an oily film 26 may be substituted if desired for the cellulose acetate coating 20, for the metal foil. The oily film normally may be a petroleum derivative light oil applied in a thin film coating by brushes or the like and serves to prevent the adhesion of any appropriate molten resinous or rubber derivative substances poured within the container, as a liquid. When such appropriate substances solidify into a block, the container 40 may be stripped therefrom, leaving the block with a slight oil residue. The oil is particularly appropriate when the melting point of the suitable material packed does not approach the disintegration temperature of the stripping film coating.

From the foregoing description of preferred embodiments of my invention, it will be recognized that the essence thereof includes the conception of packing asphalt, or substances having substantially equivalent packing properties, within cheap cardboard or like containers lined with metal foil, the latter being overcoated upon its interior surfaces with a suitable non-adherent film coating, which permits the stripping of the shipping container from the solidified block of the packed material in an easy and economical manner.

I claim:

1. A shipping container for a block of asphalt, or the like, which container includes an outer casing, an inner lining of foil, a continuous strippable plastic film on said foil, said foil adhesively secured to said casing by a bond of substantial strength, said film adhered to said foil by a bond of less strength and said film adhering to said block of material more strongly than the adhesion to said foil whereby upon removal of said block, the film clings to the surface of the material and is removed in its entirety from the surface of the foil.

2. A container as defined in claim 1, in which to insure strippable adhesion between the foil and the film an intervening oil film is disposed therebetween.

ORVILLE K. SCHMIED.
